UNITED STATES PATENT OFFICE.

JOHN O. BUERK, OF RED BANK, NEW JERSEY.

CAR-SEAT.

SPECIFICATION forming part of Letters Patent No. 389,686, dated September 18, 1882.

Application filed October 12, 1887. Serial No. 252,141. (No model.)

To all whom it may concern:

Be it known that I, JOHN O. BUERK, of Red Bank, in the county of Monmouth and State of New Jersey, have invented a new and useful Improvement in Car-Seats, of which the following is a full, clear, and exact description.

My invention relates to an improvement in car-seats, and has for its object to so improve the striker-arms of such seats that an ordinary car-seat may be simply, expeditiously, and effectually converted into a comfortable reclining-seat.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a side elevation of a car-seat having my improvement attached, illustrating the back of the seat in the ordinary position; and Fig. 2 is also a side elevation of a seat, the back being illustrated as in a reclining position. Fig. 3 is a partial plan view of Fig. 2, the striker-arm being partially in section. Fig. 4 is an elevation of one section of the striker-arms, and Fig. 5 is a transverse section 30 on line $x-x$ of Fig. 4. Fig. 6 is a skeleton view of the contour of the slot in the striker-arm, illustrating the two positions of the locking-bolt; and Fig. 7 is a detail perspective view of the bolt.

In carrying out the invention, A represents a car-seat, B the usual arms, and b the stops which limit the throw of the striker-arms D.

The striker-arms D are divided into two sections, D' and D'', of which section D' is pivoted at one extremity to the seat-arm B in the usual manner, the outer or free end, d, of this section being wider than the pivotal end, and being more or less flaring, as shown in Fig. 2, which enlargement is produced by the gradual taper of the longitudinal sides outward in opposite directions from the said pivotal end. A recess, E, is produced in the outer face of the section D', extending from the outer end to about the center, which recess is made to partake of the contour of that portion of the arm—that is, the sides are beveled from the inner end outward in opposite directions.

Within the recess E a compound longitudinal slot, E', is cut, the greater or outer portion, e, of which slot is rectangular, the inner end, e', being circular, as shown in Fig. 4. This section of the striker-arm is adapted to rest upon the stops b. The second section, D'', of the striker-arm is made tapering and of the same general contour as the contour of the recess E', into which it is adapted to enter. At the rear ends of the section D'' a perpendicular projection, F, is provided, the said section being attached to the end of the seat-back G by screw-bolts or equivalent fastening devices 65 passing through the projection and the rear of the arm into the back, as shown in Figs. 1 and 2.

Through an aperture in the reduced end of the section D'' a bolt, H, is projected, which bolt is flattened on opposite sides to a thickness equal to the width of the rectangular portion of the slot E and rounded upon the other two sides to turn in the circular portion of said slot, as shown in Fig. 6. After being 75 passed through the section D'', the bolt H enters the compound slot E, and is formed with an inner head, h, which head travels in a recess, h', in the rear of section D' at each side of the slot therein, as shown in Figs. 3 and 5. The 80 outer head, h'', of the bolt H is of greater diameter than the aperture through which it passes, and is provided with a central rectangular post, h'', whereby the bolt is turned. By means of the two heads the bolt is retained in 85 position.

In operation, when the seat-back is in the ordinary position, the section D'' telescopes with the section D', and, the bolt being turned in the circular portion of the slot E at right angles to the rectangular portion, the posts are held in positive connection, as shown in Fig. 1 and to the right in Fig. 6. To incline the back, the bolt H is given a quarter-turn, whereupon the flattened sides are brought in alignment with the rectangular portion of the slot E, and the back is allowed to fall back until the said bolt is brought in contact with the outer end wall of the slot, as illustrated in Fig. 2 and to the left in Fig. 6.

Having thus described my invention, what I claim as new, and desire to secure by Letters Patent, is—

1. The combination, with the arm of a car-

seat and the back thereof, of divided telescoping striker-arms having one section fixedly attached to the seat-back and provided with a revoluble bolt having flattened sides, said 5 bolt being adapted to lock the striker-arms in their closed position when said sides are arranged vertically, and the other section pivoted to the seat-arm and provided with a compound longitudinal slot adapted to receive said bolt, 10 operating substantially in the manner and for the purpose described.

2. In a striker-arm for car-seats, the combination, with the sections D' D'', of the revoluble bolt H, having the flattened sides H', the heads h h'', and having the rectangular post h', 15 and adapted to longitudinal movement in the slot e h' of the section D', substantially as and for the purpose specified.
